DE 202004003908 U1 5/2004

Primary Examiner — Cynthia Underwood

(74) Attorney, Agent, or Firm — Haynes and Boone, LLP

(57) **CLAIM**

The ornamental design for a locking carabineer, as shown and described.

DESCRIPTION

FIG. 1 is a perspective view of a locking carabineer;
 FIG. 2 is a left view of the locking carabineer of FIG. 1;
 FIG. 3 is a right view of the locking carabineer of FIG. 1;
 FIG. 4 is a front view of the locking carabineer of FIG. 1;
 FIG. 5 is a back view of the locking carabineer of FIG. 1;
 FIG. 6 is a top view of the locking carabineer of FIG. 1; and,
 FIG. 7 is a bottom view of the locking carabineer of FIG. 1.
